UNITED STATES PATENT OFFICE

109,308

DESIGN FOR A FINGER RING

William Silverman, Providence, R. I.

Application July 13, 1937, Serial No. 70,392

Term of patent 7 years

To all whom it may concern:

Be it known that I, William Silverman, a citizen of the United States of America, residing at Providence, in the county of Providence and State of Rhode Island, have invented a certain new, original, and ornamental Design for a Finger Ring, of which the following is a specification, reference being had to the accompanying drawing forming part thereof.

Fig. 1 is a plan view of the finger ring showing my new design.

Fig. 2 is a side elevation or edge view thereof, the opposite side having the same design features.

Fig. 3 is an end elevation showing one end of the finger ring, the opposite end having the same design features.

The dominating features of my design for a ring, reside in the combination of the specific design of the face and the specific design of the shank blended into the composite design shown.

I claim:

The ornamental design for a finger ring substantially as shown and described.

WILLIAM SILVERMAN.
